[57] CLAIM

The ornamental design for a modular locker unit primarily for outdoor use, as shown and described.

DESCRIPTION

FIG. 1 is a perspective view of a modular locker unit primarily for outdoor use.

FIG. 2 is a plan view thereof.

FIG. 3 is a perspective view of a modified version of the modular locker unit of FIG. 1 on a reduced scale wherein the umbrella has been omitted for convenience of illustration.

FIG. 4 is an exploded view of the FIG. 3 locker unit with a portion of the umbrella handle being omitted for convenience of illustration.

FIG. 5 is an enlarged fragmentary view showing the ornamentation on one of the identical doors of FIG. 3 in greater detail.

The surface of the bottom of the locker unit is substantially planar. The locker unit is symmetrical with the undisclosed doors of FIGS. 1, 3 and 4 being like the respective doors shown.

FIG. 1.

FIG. 5.

FIG. 2.

FIG. 3.

FIG. 4.
